FEEDER

George S. Smith, Chicago, Ill.

Application September 1, 1936, Serial No. 98,968

1 Claim. (Cl. 197—130)

My invention relates to typewriters, and has among its objects and advantages the provision of an improved magazine feeder for automatically delivering articles to be addressed one at a time into the typewriter.

An object of my invention is to provide a magazine feeder designed for automatically delivering cards, envelopes, and similar articles to a typewriter of conventional design and in which the feeder embodies a simple operating connection with the typewriter.

In the accompanying drawings:

Fig. 1 is a fragmentary view of a typewriter showing my invention applied thereto;

Fig. 2 is an end view of the structure illustrated in Fig. 1 taken from the position indicated by line 2—2 of Fig. 1;

Fig. 3 is a sectional view along the line 3—3 of Fig. 1;

Fig. 4 is a top plan view of the magazine feeder taken from the position indicated by line 4—4 of Fig. 2;

Fig. 5 is a sectional view along the line 5—5 of Fig. 3;

Fig. 6 is a sectional view along the line 6—6 of Fig. 3;

Fig. 7 is a sectional view along the line 7—7 of Fig. 6; and

Fig. 8 is a perspective view of the supporting mechanism for the magazine feeder, illustrating the parts in separated relation.

In the embodiment selected to illustrate my invention, I make use of a conventional typewriter 10 including a frame 12 upon which the platen 14 is rotatably mounted in the usual manner. Referring to Fig. 3, two guide rolls 16 and 18 and a curved spring member 20 are associated with the platen for holding the articles in operative relation with the platen as it is turned 40 for moving the articles into typing position on the platen. The typewriter also includes a conventional plate 22 for guiding sheets and envelopes into throat 24 for delivery to the platen.

My invention comprises a feeder 26 in the nature of a magazine designed for supporting a plurality of cards or envelopes 28 to be delivered to the platen for addressing or typing purposes. Specifically, the magazine 26 comprises a rear wall 30, a front wall 32, and end walls 34. The wall 32 is arranged in angular relation with the wall 30 and includes a section 36 arranged in slightly angular relation with the reach 38 of the wall 30. I extend the side walls 34, as at 40, to provide a mounting for shafts 42 and 44

upon which I mount a plurality of spaced rubber rolls 46 and 48, respectively.

The rolls 46 rest on the platen 14 and support the load of the magazine. Rolls 46 are arranged in frictional relation with the rolls 48 to rotate 5 the latter when the platen 14 is rotated. The rolls 48 support the inner ends of the cards 28 to have frictional relation therewith for feeding the cards one at a time into the throat 24 as the platen is turned.

Upon the inner face of each wall extension 40 I mount a bell crank 50 in which I journal one end of the shafts 42 and 44 for supporting purposes. In Figs. 5 and 7 I indicate these shafts as having reduced extensions 52 which are rotatably mounted in openings 54 in the bell crank. Each bell crank is pivotally mounted on a supporting screw 56. These screws have threaded relation with the bell cranks 50 only. Each wall extension 40 includes a reenforcing plate 57 and a slot 58 20 for the reception of a screw 60 extending therethrough and having threaded relation with its respective bell crank 50. The heads 62 of the screws 60 have pressure relation with the outer faces of the reenforcing plates 57 so that the 25 bell cranks 50 may be secured in various adjusted positions by tightening the screws 62. I arrange the slots 58 in concentric relation with the axes of the pivot screws 60. Because of the adjustable mounting of the shafts 42 and 44, the 30 bell cranks 50 may be shifted to secure precise adjustment of the rolls 46 with respect to the articles being fed.

In delivering thin and easily flexible articles to the platen, the rolls 46 are positioned closer 35 to the inner ends of the articles 28 than when feeding stiff cards and less flexible articles. Since the rolls 46 carry the magazine 26 and its load, shifting the bell cranks 50 about their pivots does not impair the tractive relation between the rolls 46 and the platen 14.

To the wall 30 I connect a bracket 64 which includes a spring clip 66 which has pinching relation with the plate 22 for balancing the magazine 26, as illustrated in Fig. 2. The bracket 45 comprises a reach 68 welded at 70 to one of the pressure elements 72 of the clip 66. The opposite end of the reach 68 is provided with a screw 74 passing through a slot 76 in a link 78 pivotally connected at 80 with a connecting element 50 82. The connecting element comprises a metallic strap having resilient properties bent back upon itself at 84 and shaped to be inserted in a loop 86 fixedly attached to the wall 30. In Fig. 8, I illustrate the loop 86 as being provided with an 88

opening 88 for the reception of a lug 90 carried by the element 82 to prevent accidental disconnection. The reach 92 of the element is bent out slightly at 94 to provide a grip facilitating connection and disconnection of the element. The spring tension of the connecting element provides effective retention for the element when placed within the loop 86.

The bracket 64 may be adjusted to support the magazine 26 in various angular positions with respect to the vertical in addition to embodying compensation for variations in structural parts of the typewriter.

In operation, the cards or envelopes 28 are placed in the magazine 26 in the manner illustrated in Fig. 3, at which time the inner edges of the cards or envelopes abut the wall 30. A weighted follower 96 is placed in the magazine 26 and rests upon the article being delivered to the typewriter. The follower includes a wall 98 and a wall 100 paralleling the wall 30 and the cards or envelopes 28, respectively. Since the rolls 48 support the inner ends of the cards 28, rotation of the platen 14 in the direction of the arrow 102 rotates the rolls 48 in the direction of the arrow 104. Such rotation of the rolls 48 moves the lowermost card or envelope into the throat 24 and into gripping relation with the roll 16 and the platen 14, after which the card or envelope is carried through the typewriter in the usual manner. As the card or envelope passes upwardly on the other side of the platen, it is brought into deflecting relation with a deflector 106 carried by the magazine 26. This deflector operates to hold the cards or envelopes in operating relation with the platen for typing purposes.

As one card or envelope is delivered to the throat 24, the succeeding card or envelope is advanced as soon as the preceding card or envelope is moved out of frictional relation with the rolls 48. In this way, the cards or envelopes are delivered to the platen 14 in slight overlapping relation, as illustrated in Fig. 3. Counter rotation of the platen 14 will return the cards or envelopes to the magazine 26 without buckling of the articles.

Referring to Fig. 3, the bend 108 in the wall 30 is positioned slightly above the lowermost card or envelope in the magazine. In this way, the wall area above the bend constitutes an abutment for the cards or envelopes, while the angular reach 38 constitutes an abutment of less abruptness, which offers less resistance to the cards as they move into the throat 24. To insure proper abutting relation between the inner edges of the cards or envelopes 28 and the wall 30, I provide the magazine with two fingers 110 which are arranged to have slight pressure relation with the lowermost articles in the magazine. These fingers engage the edges of the lowermost cards or envelopes and advance the articles in the manner illustrated in Fig. 3. The weight of the articles together with the follower 96 insures proper positioning of the articles at all times.

In Fig. 1, I illustrate the fingers 110 as including slots 112 for the reception of screws 114 having threaded relation with the reach 32 of the front wall. Since the slotted areas of the fingers 110 are arranged in parallel relation with the reach 32, the fingers 110 may be adjusted for accommodating cards or envelopes of different sizes. I slot the reach 32 of the front wall at 116 and offset the material adjacent the

slot inwardly, as indicated at 118. The offsets 118 have supporting relation with the cards or envelopes 28. The slot 116 provides an opening facilitating placement of the articles in the magazine 26.

I mount the deflector upon the arms 120 carried by the wall extensions 40. Each end of the deflector 106 is provided with a flange 122 pivotally connected with one end of its associated arm 120 by a screw 124. The deflector may be secured in various angular positions by adjustment about the axes of the screws 124. Each arm 120 is slotted at 126 to receive screws 128 having threaded relation with the wall extensions 40. These arms may be adjusted to shift the deflector 106 toward or away from the magazine 26 so as to secure an effective holding action on the cards or envelopes while typing thereon.

Two straps 130 have their ends welded to the front wall of the magazine, which straps function as deflecting elements for the cards or envelopes removed from the machine. These straps hold the cards or envelopes in spaced relation with the magazine so that the articles are spaced for grasping purposes. In Fig. 3, I illustrate the reach 38 as being provided with a strip 132 of rubber or fabric which provides a cushion for the plate 22, thus preventing scratching of the plate.

My magazine feeder embodies a simple construction, one in which the weight of the magazine together with the contents is employed for establishing a frictional drive for the feeder. This feature eliminates a special driving mechanism between the typewriter and the feeder, and the construction is such that proper tractive relation is easily attained by merely supporting the feeder on the platen. A large number of cards or envelopes may be placed in the feeder, after which the articles are delivered automatically to the typewriter as each article is typed and removed from the machine.

While I have illustrated the shafts 42 and 44 as being provided with a plurality of friction rolls, each shaft could be provided with a single roll of sufficient length. Because of the abutting relation between the inner edges of the cards or envelopes and the rear wall 30, the articles will be properly aligned when delivered to the platen 14. The overlapping relation between the articles permits counter rotation of the platen 14 without interference from the articles being delivered thereto. My magazine will operate as an accessory to any standard typewriter and necessitates no reconstruction of the machine. No parts are added to nor removed from the typewriter. Operating relation is established between the two by merely placing the magazine upon the platen.

Without further elaboration, the foregoing will so fully explain my invention that others may, by applying current knowledge, readily adapt the same for use under various conditions of service.

I claim:

A device for feeding cards, envelopes and the like to a typewriter having a rotatable platen mounted upon a platen carriage comprising a hopper consisting of back and front walls disposed at an angle with respect to each other and connecting vertical side walls, opposing plates 70 adjustably secured adjacent the lower end of each side wall, a pair of shafts extending between and journaled in said plates, oppositely arranged, registering and engaging rollers mounted upon said respective shafts, the roller upon one of 75

said shafts being positioned below and extending within the line of said front wall and forming with said back wall a discharge opening from said hopper, the roller upon the other of said shafts being adapted to extend into contact and cooperation with the platen of a typewriter, whereby power and movement is transmitted

through the contacting areas of each roller, and the adjacency of the roller which enters the hopper to the back wall thereof may be adjusted, a follower adapted to cooperate with the contents of said hopper and means for detachably securing said hopper to a platen carriage.

GEORGE S. SMITH.
